Inventor:
J. C. Merrell.

United States Patent Office.

JAY C. MERRELL, OF MEDINA, NEW YORK.

Letters Patent No. 77,511, dated May 5, 1868.

IMPROVEMENT IN WASH-BOILERS.

The Schedule referred to in these Letters Patent and making part of the same.

TO ALL WHOM IT MAY CONCERN:

Be it known that I, JAY C. MERRELL, of Medina, in the State of New York, have invented a new and useful Improved Clothes-Boiler; and I do hereby declare that the following is a full, clear, and exact description thereof, reference being had to the accompanying drawing, making part of this specification.

My invention consists in certain improvements in the ordinary clothes-boilers used on stoves, whereby the same is so arranged that it may be used on the stove in the ordinary manner, and can also be used independently of the stove, for the purpose of boiling clothes, heating water, &c.

In the accompanying drawings—

Figure 1 is a longitudinal vertical section of my improved boiler, arranged for use separate from the stove.

Figure 2 is a transverse vertical section of my improved boiler, and

Figure 3 is an end view of the same.

In constructing my improvements I take an ordinary clothes-boiler and insert through it, longitudinally, near the bottom, a tube, B, open at each end, and soldered or otherwise secured to the boiler at each end, so as to be water-tight. Over this tube, within the boiler, I locate a perforated plate, o, as shown more clearly in fig. 2, this plate o being arranged to rest loosely on ledges or flanges, so that it may be removed when not required for use. At each end of the boiler I locate a slide, C, as shown in figs. 1 and 3, of proper size to close the ends of the tube B when the boiler is to be used on the stove in the ordinary manner.

I then provide a small grate, F, of proper size and form to fit within the lower part of the tube B, as shown in fig. 1. This grate having a right-angled plate, a d, at its front end, and a vertical plate, q, at its rear end; the plate a serving to prevent the air which enters below from passing upward between it and the slide C, and causing it to pass backward under and up through between the bars of the grate F; the plate q serving to close the space underneath the rear end of the grate, and causing the flame and heat to rise and pass over it. I also propose to use one or more vertical plates H, provided with suitable base or legs to hold them in position, as represented in fig. 1, to serve as deflectors to break the direct current of the flame and heat, and thus arrest and retain the heat longer in the tube B.

I then provide a short tube, D, of proper size to fit snugly within one end of the tube B, said tube D having its outer end closed, and being provided with a vertical tube, P, to serve as a chimney and create a draught, and convey away the smoke. If desired, a cock, m, may be attached to the boiler to draw off the water, as shown in fig. 3.

The operation is as follows: When the boiler is used in the ordinary way on the stove, the plate o, with the tube D, and the grate and fixtures, are all removed, and the slides C closed, to retain the heat, and prevent it from escaping at the open ends of the tube B. Thus arranged, it is used the same as the ordinary boiler.

When, however, it is desired to use it separate from the stove, the tube B is attached, and the grate inserted, as shown in fig. 1, and a fire is then kindled on the grate within the tube B, the slide C, at the front end of the grate, being opened sufficiently to give the proper draught to the fire. The fire being thus surrounded by the water in the boiler on all sides, except at the ends, is applied in a very efficient manner, and a small amount of fuel made to answer the purpose. By these means the boiler may be used independent of the stove, and the necessity for a hot fire in the latter entirely obviated, which in warm weather is a great object. When the boiler is thus used, it may be located out of doors, or in any out-building; and when thus located, charcoal may be used for heating it, without the deleterious effects that would arise from its use in the house. When thus used, the boiler may be set on the floor, or on a bench or table, as the water below the tube B will prevent any danger from fire. It may be desirable, especially if used out of doors, to surround the boiler with a sheet-iron or other metallic case, as represented by L in fig. 1, to prevent a loss of the heat by radiation, or a cooling of the boiler and its contents by cold currents of air.

By this improvement the boiler may be used as an independent or auxiliary furnace, for boiling clothes,

heating water, or any similar purpose, thus leaving the whole of the stove to be occupied for other purposes; and this, especially with farmers and others living in the country, is oftentimes very desirable.

Having thus described my invention, what I claim, is—

The boiler A, provided with the tube B and slides C, and having the auxiliary tube D and grate F arranged for use in connection therewith, for the purpose of adapting the boiler to use either with or independent of the stove, substantially as described.

JAY C. MERRELL.
